CLAIM

I claim the ornamental design for a hand carried tool box, as shown and described.

DESCRIPTION

FIG. 1 shows a front top perspective view of an embodiment of my tool box design, with an identical shown stacked beneath it to aid in perspective.

FIG. 2 shows a long-side layout view of the embodiment of my tool box design, with the opposing long-side view being identical.

FIG. 3 shows a short-end layout view of the embodiment of my tool box design, with the opposing short-end view being identical.

FIG. 4 shows a top plan view of the embodiment of my tool box design; and,

FIG. 5 shows a bottom plan view of the embodiment of my tool box design.

The broken line showing in FIG. 1 is included for the purpose of illustrating environmental structure and forms no part of the claimed design.
